UNITED STATES PATENT OFFICE.

EDWIN C. RENAUD, OF ST. JOSEPH, MISSOURI.

RADIATOR-CAP LOCK.

Application filed May 1, 1922. Serial No. 557,499.

To all whom it may concern:

Be it known that I, EDWIN C. RENAUD, a citizen of the United States, residing at St. Joseph, in the county of Buchanan and State of Missouri, have invented a certain new and useful Improvement in Radiator-Cap Locks, of which the following is a specification.

My invention relates to improvements in radiator cap locks. It relates particularly to cap locks for automobile radiator caps having motor meters mounted therein.

One of the objects of my invention is to provide a cap lock adapted to be applied to filling tubes of different diameters without requiring devices of different sizes.

A further object of my invention is the provision of a novel adapter having means for releasably locking thereto a cap and having an annular flaring seat adapted to center itself and to fit filling tubes of different diameters and having novel means for holding the adapter from felonious removal from the filling tube on which it is mounted.

Still another object of my invention is to provide a novel cap lock of the kind described, which is simple, cheap to make, durable, not liable to get out of order, which can be easily and quickly applied to the majority of filling tubes now in use and which will securely hold the radiator cap and a motor meter carried thereby from unauthorized removal.

The novel features of my invention are hereinafter fully described and claimed.

In the accompanying drawing, which illustrates the preferred embodiment of my invention,

Fig. 1 is a front elevation of my improved cap lock, shown applied to a radiator filling tube.

Fig. 2 is an enlarged vertical sectional view, partly broken away, on the line 2—2 of Fig. 1.

Fig. 3 is a horizontal section on the line 3—3 of Fig. 2.

Fig. 4 is a horizontal section on the line 4—4 of Fig. 2.

Fig. 5 is a vertical sectional view on the line 5—5 of Fig. 2.

Fig. 6 is a vertical sectional view of a portion of the adjusting screw and parts connected therewith, the adjusting screw and pivoted locking members being shown in the unlocked position.

Similar reference characters designate similar parts in the different views.

1 designates an ordinary radiator filling tube, in which is mounted the lower end of a vertical tubular adapter 2, having an upwardly and outwardly flaring annular seat 3, in which is mounted a ring gasket 4, which bears against the upper end of the filling tube 1.

The adapter 2 may be provided with an annular downwardly extending flange 5, which projects below the upper end of the filling tube and which serves as a guard for preventing the insertion of wires or instruments into the filling tube, and also to prevent any undue lateral tilting of the adapter.

The upper end of the adapter is externally threaded and has fitted thereon an ordinary radiator cap 6, having a central vertical hole through which extends the threaded stem 7, of a motor meter 8, of an ordinary type.

To hold the cap 6 from being unscrewed from the adapter 2, the latter has mounted in it an ordinary lock casing 9, adapted to receive a key 10, and provided with an inwardly and outwardly movable bolt 11. This casing 9 may contain any well known lock mechanism by which the key 10 operates the bolt 11. The latter, in the locking position, shown in Figs. 2 and 4, is in the path of movement of a downwardly extending flange 12, of a flat horizontal plate 13, having a hole through which extends the stem 7. A nut 14 mounted on the stem 7 bears against the lower side of the plate 13, and clamps the latter against the under side of the cap 6. A lock nut 15 mounted on the stem 7 bears against the under side of the nut 14. A screw cap 16 is fitted in the usual manner on the lower end of the stem 7.

The cap 6 has a downwardly extending projection 17, Figs. 2 and 4, which extends through a hole provided in the plate 13, which holds the latter from turning with respect to the cap.

By turning the cap 6 in the proper direction, it may be removed from the adapter 2, the key 10 having been previously operated to withdraw the bolt 11 out of the path of the flange 12.

For locking the adapter 2 to the filling tube 1, the adapter is provided with a central portion 18 connected with the body by

radial ribs 19 and provided with a central vertical hole in which is vertically slidably mounted a vertical screw 20 having a threaded upper end on which is fitted a wing nut 21, which bears against a nut 22, mounted on the upper side of the central portion 18. One side of the screw 20, has a longitudinal flat portion 23, against which is fitted a projection 24, Fig. 5, of the portion 18. The projection 24 holds the screw 20 from turning in the central portion 18.

The lower end of the screw 20 has a head 25, upon which rests a horizontal member comprising a plate 26, having at opposite sides respectively two pairs of upwardly extending ears 27. Located between each pair of ears 27 on a horizontal pin 28 mounted in said ears is a right-angled locking member 29. The locking members 29 are disposed diametrically opposite to each other at opposite sides respectively of the central portion 18. The latter has a downwardly converging flaring surface 30, which is adapted to contact with the locking members 29 at the inner sides of the pins 28, so as to swing the locking members from the depending position shown in Fig. 6 to the horizontal position shown in Figs. 2 and 3, in which last named position, the locking members 29 extend across and contact with the lower end of the filling tube 1.

In mounting my improved cap lock on a filling tube, the cap 6 is removed from the adapter 2, and the nuts 21 and 22 are turned so as to permit the screw 20 to slide downwardly to the position shown in Fig. 6, in which position the longer arms of the locking members 29 will be depending, and in this position will pass through the filling tube 1.

The adapter 2 is then inserted at its lower end portion into the filling tube, following which the nuts 21 and 22 are turned so as to lift the screw 20 to the position shown in Fig. 2, thereby lifting the member 26 and with it the locking members 29 which, in their upward movement will contact with the flaring portion 30 and will be swung by the latter to the position shown in Fig. 2, in which position they will lockingly engage the lower end of the filling tube.

The adapter 2 will thus be securely held against removal from the filling tube 1, after the cap 6 has been screwed onto the adapter, and the key 10 operated to slide the bolt 11 into the path of the flange 12. Access to the nuts 21 and 22 cannot be had until the proper key 10 is inserted in the lock casing 9 and operated to withdraw the bolt 11 from the path of the flange 12, thus preventing unauthorized removal of the motor-meter, cap or adapter from the machine.

By holding the screw 20 from turning in the adapter, turning of the latter on the filling tube will not loosen the nuts 21 and

22. Such turning of the adapter will only cause the screw 20 to turn in the member 26.

If at any time, it is desired to remove the adapter from the filling tube and mount it on the filling tube of another machine, the cap 6 is removed in the manner already described, upon which access may be had through the adapter to the nuts 21 and 22. The latter are then turned so as to permit the screw 20 and member 26 to lower, to the position shown in Fig. 6, upon which the locking members 29 will swing to the contracted position shown in Fig. 6. The locking members 29 will then pass through the filling tube 1, and the adapter with the parts carried thereby may be removed from the filling tube.

The internal diameter of the annular flange 5, and the external diameter of the lower portion of the adapter 2 may be such as to permit the application of the adapter to filling tubes varying considerably in diameter.

When the cap 6 is removed, water may be poured into the radiator through the adapter 2.

I do not limit my invention to the structure shown and described, as many modifications, within the scope of the appended claims, may be made without departing from the spirit of my invention.

What I claim is:—

1. In a radiator cap lock, a tubular adapter arranged to be fitted on the filling tube of a radiator, means for releasably locking the adapter to the filling tube, a screw cap having threaded removable connection with the upper end of said adapter and having a vertical hole, a motor meter having a threaded stem extending through said hole, a locking member having a hole through which said stem extends, a nut on said stem arranged to clamp said locking member against the inner side of said cap, means for holding the locking member from turning on said stem, and a locking bolt movable on said adapter into and out of the path of movement of said locking member when the latter is turned with said cap, substantially as set forth.

2. In a radiator cap lock, a tubular adapter arranged to be fitted on the filling tube of a radiator, means for releasably locking the adapter to the filling tube, a screw cap having threaded removable connection with the upper end of said adapter and having a vertical hole, a motor meter having a stem extending through said hole, a locking member through which the stem extends, securing means on said stem bearing against said locking member for holding the stem against withdrawal from said cap and said locking member, means for holding the latter from turning on said cap, and a locking bolt movable on said adapter into

and out of the path of movement of said locking member when the latter is turned with said cap, substantially as set forth.

3. In a radiator cap lock, a tubular adapter having an annular flaring seat adapted to be fitted against the upper ends of filling tubes of different diameters, a cap adapted for releasable attachment to the upper end of said adapter, means for locking said cap from removal from the adapter, and means accessible only through the interior of the adapter for releasably locking the latter to a filling tube on which the adapter may be fitted, substantially as set forth.

4. In a radiator cap lock, a tubular adapter having an annular seat adapted to bear against the upper end of a filling tube, and having an abutment, a cap fitted on the upper end of said adapter and adapted for removal therefrom, a vertically movable member, means carried by said adapter for vertically adjusting said member, and a locking member movable on the vertically movable member to and from a locking position with respect to the lower end of said filling tube and adapted when the vertically movable member is in the unlocked position to pass through said filling tube, and when the vertically movable member is moved vertically to the locking position said abutment engages the locking member and moves it outwardly to a position in which the locking member will have locking engagement with the lower end of said filling tube, substantially as set forth.

5. In a radiator cap lock, a tubular adapter having an annular seat adapted to bear against the upper end of a filling tube, and having an abutment, a cap fitted removably on the upper end of said adapter, a vertically movable member, means carried by said adapter for vertically adjusting said member to and from a locking position, and a locking member pivoted to the first named member so as to swing thereon to and from a locking position in which it will engage the lower end of said filling tube, and arranged to be struck and swung by said abutment to the locking position when the first named member is moved to the locking position, the locking member in the unlocked position being adapted for insertion and withdrawal through the filling tube, substantially as set forth.

6. In a radiator cap lock, a tubular adapter adapted to bear against the upper end of a filling tube and having an abutment, a cap removably fitted on the upper end of said adapter, a vertically movable member, vertically adjustable means including a screw supported by said adapter and arranged to support and to vertically adjust said movable member, and a locking member carried by said movable member and

arranged to engage said abutment and to be moved thereby to the locking position when the movable member has been adjusted to the locking position, the locking member in the locking position being adapted to engage the lower end of said filling tube, thereby holding the adapter against removal, the locking member in the unlocked position being adapted for insertion and withdrawal through the filling tube, substantially as set forth.

7. In a radiator cap lock, a tubular adapter adapted to bear against the upper end of a filling tube, a cap removably fitted on the upper end of said adapter, a screw vertically slidable in said adapter, a nut fitted on said screw and bearing against the upper side of said adapter, a member supported by and movable with said screw, and a locking member carried by said movable member and arranged to strike and to be forced by said adapter to the locking position, when the movable member is moved upwardly to the locking position, the locking member in the unlocked position being adapted for insertion and withdrawal through said filling tube, and in the locking position engaging the lower end of the latter, substantially as set forth.

8. In a radiator cap lock, a tubular adapter adapted to bear against the upper end of a filling tube, a cap removably fitted on the upper end of said adapter, a screw vertically slidable in said adapter, a nut fitted on said screw and supported by said adapter, a member supported by and movable with said screw, and one or more locking members pivoted to said movable member and arranged to strike and be moved by the adapter to a locking position engaged with the lower end of said filling tube, when the movable member is moved upwardly to a locking position and adapted for insertion and withdrawal through said filling tube when in the unlocked position, substantially as set forth.

9. In a radiator cap lock, a tubular adapter adapted to bear against the upper end of a filling tube, a cap removably fitted on the upper end of said adapter, means for locking the cap from removal from said adapter, a screw vertically slidable in said adapter, a nut fitted on said screw and supported by the adapter, a locking member, and a movable member carried by said screw, the locking member being pivoted to said movable member and adapted when the latter is lifted to a locking position to engage and to be swung by the adapter to a locking position abutting against the lower end of said filling tube and in the unlocked position being adapted for insertion and withdrawal through the filling tube, substantially as set forth.

10. In a radiator cap lock, a tubular

adapter having an annular flaring seat adapted to bear against the upper ends of filling tubes of different diameters, a cap removably fitted on the upper end of said adapter, means for releasably locking said cap to said adapter, a screw vertically slideable in said adapter and held thereby against rotation, a nut fitted on said screw and supported by said adapter, a member supported by said screw and vertically movable therewith, and one or more radially disposed locking members pivoted on horizon-

tal axes to said movable member and arranged when the latter is moved upwardly to the locking position, to engage and be swung by said adapter to the locking position in engagement with the lower end of said filling tube and adapted in the unlocked position for insertion and withdrawal through the filling tube, substantially as set forth.

In testimony whereof I have signed my name to this specification.

EDWIN C. RENAUD.
